UNITED STATES PATENT OFFICE.

FRED C. AREY, OF OAK PARK, ILLINOIS, ASSIGNOR TO NORTHWESTERN EXPANDED METAL COMPANY, OF CHICAGO, ILLINOIS, A CORPORATION OF ILLINOIS.

RIBBED EXPANDED-METAL LATHING.

1,164,160.

Specification of Letters Patent.

Patented Dec. 14, 1915.

Application filed April 21, 1913. Serial No. 762,603.

To all whom it may concern:

Be it known that I, FRED C. AREY, a citizen of the United States, residing at Oak Park, county of Cook, State of Illinois, have invented a certain new and useful Improvement in Ribbed Expanded-Metal Lathing, and declare the following to be a full, clear, and exact description of the same, such as will enable others skilled in the art to which it pertains to make and use the same, reference being had to the accompanying drawings, which form a part of this specification.

There are in common use two kinds of expanded metal lathing, the first consisting of simple sheets of expanded metal and the other comprising sheets having expanded or reticulated portions separated by solid portions which are pressed laterally to form projecting ribs. The first kind of lathing makes it necessary to employ spacing devices of some kind between the lathing and the supporting members in order that the plastic concrete or plaster can pass through the lathing and cover the back side thereof as well as the front side. This construction has the disadvantage of requiring spacing devices or furring strips separate from the lathing itself, thus greatly increasing the time required to place the lathing in position over that which would be necessary in order to fasten merely the sheets of lathing in place. The spacing devices and the furring strips, as well as the ribs on ordinary ribbed lathing have the disadvantage that it is difficult to get the concrete or plaster into all of the crevices and about all of the exposed surfaces in such a way that the plastic material will be effectively keyed in place and thoroughly cover all of the metallic surfaces so as to protect them. Consequently some portions of the lathing will always be left more or less unprotected.

The object of the present invention is to produce a simple and novel sheet of lathing which shall have a continuously reticulated surface and be provided with strengthening and spacing ribs which will not interfere with the continuity of the face of the sheet, whereby the lathing will be made strong and rigid, and places itself apart from a support

or supports to which it may be fastened, while at the same time it presents the same exposed face as the ordinary unribbed expanded metal sheets and permits the plastic material to be applied easily and conveniently without danger that the lathing will not be fully protected or that some of the plastic material will not be keyed effectually.

The various features of novelty whereby my invention is characterized will herein-after be pointed out with particularity in the claims; but, for a full understanding of my invention and of its object and advantages, reference may be had to the following detailed description taken in connection with the accompanying drawings, wherein:

Figure 1 is a front view of a sheet of lathing arranged in accordance with a preferred form of my invention; Fig. 2 is an end view of the sheet on a somewhat enlarged scale; Fig. 3 is a front view of a fragment of one of the strips of which the sheet is made; Figs. 4 and 5 are sections taken transversely through the adjoining edges of two of the strips, illustrating the ribs arranged in accordance with two of the modifications of my invention; and Figs. 6 and 7 are views similar to Figs. 4 and 5, illustrating modified ribs in cases where the several strips are integrally connected together.

In carrying out my invention I form a sheet having about the same dimensions as those usually given the ordinary plain expanded metal lathing, by placing side by side and permanently fastening together a series of narrow strips each of which consists of a body of reticulated metal having a portion at each side bent laterally at right angles to form a flange; the flanges of contiguous sheets being riveted or otherwise permanently fastened together and thus providing the sheet with a series of thin stiffening and spacing ribs on the rear side and leaving the face of the sheet in the form of a continuous reticulated surface. I make each strip about four inches wide so that a twenty-four inch sheet will be composed of about six individual strips and will have on the rear side seven parallel ribs extending lengthwise thereof.

In the preferred arrangement I take a long narrow strip of sheet metal and slit it along parallel broken lines inclined somewhat to the side edges of the strip, the slitted portions in each line lying opposite unslit portions in adjacent lines; and borders an inch or so in width at the sides being left unslit. The borders are bent at right angles to the plane of the sheet on the same side thereof so as to form flanges along the edges of the slitted portions. When the flanges are pulled apart the slitted body is expanded so as to form it into two series of strands extending transversely of each other and forming an approximately diamond-shaped mesh as indicated at 1. This mesh extends continuously across the strip from one flange to another so that when two strips are laid side by side with their flanges, 2, contacting, they produce an expanded strip of double width having an unbroken surface, the edges of the two contacting ribs simply taking the place of one of the longitudinal strands. The same condition exists when more than two strips are laid side by side. The contacting flanges may be secured together in any suitable way, preferably by punching the metal of one flange through an opening in the other and upsetting so as to form a hollow rivet, 3, which permanently unites the two flanges together. Consequently when enough of the strips are fastened together they produce a sheet of lathing of the usual size on which the plastic concrete or plaster may be placed with the same ease and with the same certainty that perfect results will be obtained as in the case of a simple expanded sheet free from ribs or spacing devices. At the same time, however, the sheet has great strength and rigidity and may quickly and easily be secured in its intended position.

If desired, the flanges may be bent laterally at their free edges. In Fig. 4 contiguous flanges have their edges bent laterally in opposite directions as indicated at 4 and 5, thus making the composite stiffening rib take the form of an I-beam. In Fig. 5 the two flanges are both bent in the same direction, as indicated at 5 and 6.

In some instances it may be desirable to form the several strips of which a sheet is to be composed integral with each other. In such case the connecting flanges, 7, between adjacent strips are comprised of a single piece folded in the middle as indicated in Fig. 6 and riveted together as heretofore described. A rib so formed may be stiffened by bending the metal to form a flange or flanges along its outer edge; one such arrangement being illustrated in Fig. 7, where 8 represents the rib and 9 a stiffening flange along its edge.

While I have illustrated and described

only a single preferred arrangement in which the reticulated metal is produced in a simple and efficient manner, I do not desire to be limited to this exact arrangement; I intend to cover all forms and arrangements which fall within the terms employed in the definitions of my invention constituting the appended claims.

I claim:

1. As an article of manufacture, a sheet of lathing in the nature of a "hyrib" structure made up of a series of connected, long, narrow strips, each strip comprising an expanded metal panel of open mesh bordered at the sides by solid metal, the solid metal portions being bent laterally to form flanges, 75 and the strips being permanently connected through their flanges so as to produce a continuously reticulated sheet having a series of thin longitudinal ribs on one side thereof.

2. As an article of manufacture, a sheet of lathing in the nature of a "hyrib" structure made up of a series of connected, long, narrow strips, each strip comprising a panel of open mesh bordered at the sides by solid metal, the solid metal portions being bent laterally to form flanges, and the strips being permanently connected through their flanges so as to produce a continuously reticulated sheet having a series of thin longitudinal ribs on one side thereof, and the free edges of said flanges being bent transversely of the flanges to stiffen them.

3. As an article of manufacture, a long narrow sheet of lathing in the nature of a "hyrib" structure having its surface composed entirely of expanded metal in the form of narrow strands connected together and forming an open mesh, said sheet being made up of a series of long narrow strips having flanges permanently connected together, each strip between the flanges being made up of narrow strands extending continuously from one flange to the other.

4. As an article of manufacture, a long narrow sheet of lathing having its surface composed entirely of expanded metal in the form of strands connected together and forming an open mesh, said sheet being made up of a series of long strips having a width of a few inches only and provided with flanges permanently connected together and constituting a "hyrib" structure.

5. As an article of manufacture, a long narrow sheet of lathing having its surface composed entirely of expanded metal in the form of strands connected together and forming an open mesh, said sheet being made up of a series of long strips having a width of a few inches only and provided with solid flanges permanently connected together and constituting a "hyrib" structure.

6. As an article of manufacture, a long narrow sheet of lathing having its surface

composed entirely of expanded metal in the form of strands connected together and forming an open mesh, said sheet being made up of a series of long narrow strips provided with solid flanges permanently connected together and constituting a "hy-rib" structure.

In testimony whereof, I sign this specification in the presence of two witnesses.

FRED C. AREY.
